Primary Examiner—Ruth McInroy(74) *Attorney, Agent, or Firm*—Anna A. Wetzels(57) **CLAIM**

The ornamental design for a protective plate for a welding filter in a welding helmet, as shown and described.

DESCRIPTION

FIG. 1 is a perspective view of a protective plate for a welding filter in a welding helmet showing my new design;

FIG. 2 is a front view thereof;

FIG. 3 is a left side view thereof, the right side being a mirror image;

FIG. 4 is a rear view thereof;

FIG. 5 is a top view thereof; and,

FIG. 6 is a bottom view thereof.

The details shown in broken lines form no part of the claimed design.

It is certified that error appears in the above-identified patent and that said Letters Patent is hereby corrected as shown below:

This certificate supersedes the Certificate of Correction issued on June 23, 2015. The certificate which issued on June 23, 2015 is vacated since the information in heading of issued cofc does not correspond to the subject matter mentioned to be corrected in patent. The errors in the Certificate of Correction corresponds to the correct patent number 8865734 . The Certificate of Correction which issued on June 23, 2015 was published in error and should not have been issued for this patent.

Signed and Sealed this
Fourteenth Day of July, 2015

Michelle K. Lee
Director of the United States Patent and Trademark Office
